J. W. BURTON,
SPARK PLUG TESTER,
APPLICATION FILED SEPT. 30, 1916.

Patented Mar. 11, 1919.

FIG. 1.

FIG. 2.

J. W. Burton
Inventor

By *Geo. Himmel.*

Attorney

UNITED STATES PATENT OFFICE.

JAMES WILLIAM BURTON, OF WELCH, WEST VIRGINIA.

SPARK-PLUG TESTER.

1,297,087.

Specification of Letters Patent. Patented Mar. 11, 1919.

Application filed September 30, 1916. Serial No. 123,142.

To all whom it may concern:

Be it known that I, JAMES WILLIAM BURTON, a citizen of the United States, residing at Welch, in the county of McDowell and 5 State of West Virginia, have invented certain new and useful Improvements in Spark-Plug Testers, of which the following is a specification.

The present invention relates to electrical 10 testing devices and has particular reference to a new and useful improvement in spark plug testers.

An object of my invention is to provide a simple and easily adjusted testing device 15 for use in determining, without removal, whether a spark plug is delivering a proper spark or not.

Another object of my invention is to provide a device of the character described 20 which may be applied to any of the standard spark plugs now in use without removing the spark plug or making any changes in the ignition system of an internal combustion engine.

25 A further object of my invention is to provide a device of the character described which may be cheaply manufactured, quickly and easily applied for use, is effective in operation and conveniently adjustable.

30 Other objects and advantages to be derived from the use of my improved spark plug tester will appear from the following detailed description and the claim, taken with an inspection of the accompanying 35 drawing, in which:

Figure 1 is a perspective view of a spark plug tester embodying the improvements of my invention; and

Fig. 2 is a longitudinal sectional view of 40 the same in operative position.

Referring more particularly to the drawing, wherein similar characters of reference designate like and corresponding parts throughout the various views, 10 designates 45 the body of my improved testing device, the same preferably being formed of insulating material, such as wood, hard rubber or the like.

The body 10 carries a terminal in the form 50 of a bolt 11 having a knurled connecting nut 12 for contact with the top surface of an internal combustion engine cylinder. The opposite end of the bolt is provided with a spherical head 13 having a sparking point 14 carried thereby. An adjustable spark-

ing terminal is provided in the form of a rod 15 having one end thereof in proximity to the end of the sparking terminal 14, said rod 15 being threaded as at 16 for adjustment in a bracket 17, said bracket being secured to the body 10 by means of a bolt. A spring arm 19 is retained in connection with the bolt by means of the nut 20, the free end of said spring arm 19 being bifurcated to provide spaced fingers 21 to engage beneath the connection nut 22 of a standard spark plug 23. The rod 15 is mounted adjacent its free ends in a bracket 24, said bracket being carried by the body 10, by means of a bolt 25.

A portion of an internal combustion engine is shown and designated 26. The free end of the rod 15 is provided with a handle 28 formed of hard rubber or other insulating material.

In use the nut 12 is engaged with the top surface of the engine cylinder 26 and the arm 19 is engaged with the binding post of the spark plug. By adjusting the rod 15 to the proper gap the user may readily determine whether the spark plug in question is operating efficiently. I desire to lay particular stress upon the extreme simplicity of my improved spark plug tester. In view of the simplicity of the device and its obvious advantages a further enlargement of the description is unnecessary.

From the above description taken in connection with the accompanying drawing, it is thought that a clear and comprehensive understanding of the construction, operation and advantages of my invention may be had, and while I have shown and described the device as embodying a specific structure, I desire that it be understood that such changes may be made in said structure as do not depart from the spirit and scope of the invention as claimed.

Having thus fully described my invention, what I claim as new and desire to secure by Letters Patent, is:

A spark plug tester including a flat base formed of insulating material, a stationary terminal on one end thereof, brackets immovably mounted on the base, one of said brackets being formed with a screw threaded bore, an adjustable terminal comprising a rod having a screw threaded portion rotatably supported by said bracket, the screw threaded portion thereof engaging in the

253
screw threaded bore of one of the brackets, an insulating handle piece engaged with one end of the rod, the free end of the rod being adapted for arrangement in proximity to the stationary terminal, a contact member engaged with the stationary terminal and extending for a distance beyond the oppo-

site side of the base, and a curved spring arm having a bifurcated free end secured to the base and connected to the adjustable 10 terminal.

In testimony whereof, I affix my signature hereto.

JAMES WILLIAM BURTON.
